US0D1104092S

(12) **United States Design Patent** (10) **Patent No.:** **US D1,104,092 S**
(45) **Date of Patent:** **** Dec. 2, 2025**

(54) **WELDING TORCH**

(71) Applicant: **DAIHEN CORPORATION**, Osaka (JP)

(72) Inventor: **Chikara Takata**, Osaka (JP)

(73) Assignee: **DAIHEN CORPORATION**, Osaka (JP)

(**) Term: **15 Years**

(21) Appl. No.: **35/520,449**

(22) Filed: **Mar. 29, 2023**

(80) **Hague Agreement Data**

Int. Filing Date: **Mar. 29, 2023**

Int. Reg. No.: **DM/229158**

Int. Reg. Date: **Mar. 29, 2023**

Int. Reg. Pub. Date: **Mar. 29, 2024**

(30) **Foreign Application Priority Data**

Sep. 30, 2022 (JP) ..... 2022-021227 D
Sep. 30, 2022 (JP) ..... 2022-021228 D

(57) **CLAIM**

The ornamental design for a welding torch as shown and described.

DESCRIPTION

1.—Welding torch

Fig. 1.1 is a right, front, perspective view of a welding torch showing our new design;

Fig. 1.2 bottom, left, perspective view thereof;

Fig. 1.3 is a front elevation view thereof;

Fig. 1.4 is a back elevation view thereof;

Fig. 1.5 is a top plan view thereof;

Fig. 1.6 is a bottom plan view thereof;

Fig. 1.7 is a right elevation view thereof;

Fig. 1.8 is a left elevation view thereof;

Fig. 1.9 is an enlarged detail view of the nozzle tip shown removed for clarity;

Fig. 1.10 is a center horizontal cross-sectional view taken along line 1.10-1.10 of the nozzle tip shown in Fig. 1.9 shown removed for clarity;

Fig. 1.11 is an exploded view of the welding torch in Fig. 1.1.

The article is a welding torch used with welding devices.

1 Claim, 11 Drawing Sheets
